CONDUIT BLOCK MAKING MACHINE

Paul E. Rauch, St. Louis County, Mo., assignor of one-half to John M. Mohan, St. Louis County, Mo.
Filed Mar. 6, 1961, Ser. No. 93,476
5 Claims. (Cl. 25—34)

This invention relates in general to conduit blocks and, more particularly, to certain new and useful improvements in machines for making same. This application is a continuation-in-part of my co-pending application, filed October 5, 1959, Serial No. 844,415 now Patent Number 2,994,936, entitled "Conduit Block Making Machine."

It is an object of the present invention to provide a conduit block making machine which is adapted for producing blocks having conduits beveled at their opposite ends to prevent cutting of cable coverings through inadvertent misalignment of adjacent blocks.

It is a further object of the present invention to provide conduit blocks having constant diameter dowel pin openings extending continuously from end to end thereof whereby sections of varying length cut from such blocks will integrally contain openings for dowel pins, and thus, not require the independent formation of such openings as is presently necessary.

It is another object of the present invention to provide a conduit block making machine which is adapted for highly reliable, economical, and durable performance, having a relative simplicity of parts, so that the same is not subject to frequent "down time."

It is a further object of the present invention to provide a conduit block making machine which incorporates novel means for forming continuous dowel pin openings in conduit blocks which obviates the use of lower, upwardly extending mold pins, thereby avoiding damage to the pallet as well as to produced blocks by misalignment of such pins.

It is a still further object of the present invention to provide a conduit block making machine which is relatively simple in operation, requiring minimum supervision and wherein the same will produce conduit blocks of consistently excellent quality.

Other objects and details of the invention will be apparent from the following description, when read in connection with the accompanying drawings (five sheets) wherein:

FIGURE 1 is a front elevational view of a conduit block making machine constructed in accordance with and embodying the present invention.

FIGURE 2 is a horizontal transverse section taken on the line 2—2 of FIGURE 1.

FIGURE 3 is a horizontal transverse section taken on the line 3—3 of FIGURE 1.

FIGURE 4 is a horizontal transverse section taken on the line 4—4 of FIGURE 2.

FIGURE 5 is a vertical transverse section taken on the line 5—5 of FIGURE 3.

FIGURE 6 is a horizontal transverse section taken along the line 6—6 of FIGURE 4.

FIGURE 7 is a horizontal transverse section taken on the line 7—7 of FIGURE 5.

FIGURE 8 is a vertical transverse section of another form of forming plate constructed in accordance with and embodying the present invention.

FIGURE 9 is a horizontal transverse section taken on the line 9—9 of FIGURE 1.

FIGURE 10 is a fragmentary vertical transverse section taken on the line 10—10 of FIGURE 9.

FIGURE 11 is an elevational view of a conduit block formed by operation of the present invention.

2

FIGURE 12 is a horizontal view taken on the line 12—12 of FIGURE 11.

Referring now by reference characters to the drawings which illustrate the preferred embodiment of the present invention, A broadly designates a conduit block making machine comprising a pair of horizontally spaced apart, vertically extending columns or posts 1, 1', which at their lower ends are secured upon a base frame structure, indicated at 2, and located below floor level, being mounted upon a foundation F. Provided for vertical reciprocal travel along columns 1, 1' is a motor head or carriage 3 comprising a pair of sleeves or bearing housings 4, 4' for movement along columns 1, 1', respectively, and a central or intermediate frame body portion 5 which includes upper and lower transverse, parallel plates 6, 7, respectively. Mounted on upper plate 6 is a plurality of hydraulic motors m which may be of any selected number, as for example, nine, with the central motor m' being supported upwardly of the others upon a suitable mounting plate 6'. The drive shaft of each motor m, which projects downwardly, is engaged to an elongated, vertical shaft or spindle 8; said latter being axially parallel to columns 1, 1', and each being journaled in a bearing 9 mounted in lower transverse plate 7 of frame body portion 5 of head 3. Each shaft 8 carries at its lower end a packing head p. Shafts 8 are adapted for uniform rate of rotation, as by means more fully described in my aforesaid copending application which forms no part of the present invention.

Secured to the under face of lower transverse plate 7 are four collars 100 in tandem arrangement, each being located in the space centrally of four adjacent shafts 8 and thus disposed at 90 degree intervals about the center shaft. Secured, as by a set screw 102, within each collar 100 is the upper end of an elongated rod or dowel pin core holder 101 having a diameter slightly less than the diameter of the bore of the related collar 100 and being so engaged that its upper end face is spaced from transverse plate 7. It will be seen that said rods 101 are adapted for limited "play" within their respective collars and coact with the same to thereby provide a, commonly referred to, "sloppy" fit. Proximate their upper ends, adjacent collars 100, the rods 101 of each transversely aligned pair are interconnected by a transverse pin 103 which projects at its ends freely through aligned bores in said rods 101, and has engaged at its ends securing elements such as cotter pins 104. By means of pins 103 the outer limits of the intervening space between rods 101 will be controlled, yet said rods 101 will be permitted, within the limits provided, restricted independent movement, for purposes presently appearing.

The lower end of each rod 101 is located immediately upwardly of the upper end of packing heads p of shafts 8, and at such end is tapered as at 105. Said rods 101 are each drilled in their lower end face to form an upwardly extending socket 106 for receiving the upper, reduced end 107 of a dowel pin core 108; there being a set screw t for securing the latter in position. Said core 108 is provided with a shoulder 109 for abutment against the adjacent, confronting lower end face of the related rod 101. The lower ends of cores 108 terminate immediately upwardly of the lower end faces of packing heads p and are tapered at their lower end extremity (FIGURE 4). Mounted upon the upper ends of columns 1, 1' is an open, rectangular support frame 12 formed, preferably of channel stock. Supported upon brackets (not shown) fixed to each column 1, 1' and the adjacent portion of frame 12 are vertically presented hydraulic cylinders 16, 16', respectively, each having at its lower end a piston 17, 17', respectively, which are engaged to a fitting or boss b provided upon the related sleeve 4, 4' of head 3 whereby

upward and downward sliding movement of said head 3 may be effected, responsive to the direction of the stroke of piston 17, 17'.

Hydraulic motors *m* are each connected through intake and outlet conduits with related manifolds, each of which is connected at its opposite ends to flexible hose connections 20, 20', for communication with a pump and source of fluid (not shown) of a conventional hydraulic system. It is to be observed that individual, selected motors of the total group may be operated through a fluid control system (not shown) which conforms to well known practice, so that an operator may only operate certain of the motors for specialized molding operations.

Hose sections 20, 20' are of such length as to accommodate the vertical travel of motor head 3. To assist in the upward movement of each of said sections 20, 20', upon return travel of head 3, there is provided a counterweight 23 for each of said hose sections 20, 20'; said counterweight 23 being located outwardly of the adjacent column 1, 1' and being carried at the end of a cable 24, which extends upwardly and is trained over a pair of inner and outer horizontally aligned pulleys 25, 25', and thence led downwardly for securing, as by clamp 26, to the related hose section 20, 20'. Said pulleys 25, 25' (there being four such pair) are mounted on rods 27, 27', respectively, which are fixed at their ends in parallel frame members 28 presented at the upper ends of uprights 29, the lower ends of which are welded or otherwise secured upon frame 12; there being braces 30 for rigidifying the pulley support structure.

With reference to FIGURE 1, it will thus be seen that as motor head 3 travels downwardly along columns 1, 1', hose section 20, 20' will likewise be caused to extend downwardly at their inner ends, causing a simultaneous raising of their respective counterweights 23, as shown in phantom lines. However, upon upward or return travel of said motor head 3, counterweights 23 will descend, through gravity, and effect an upward pulling upon the related hose sections 20, 20' to assure their restoration to initial, fully serviceable position.

It is apparent that conduit block machine A may be provided with any number of such motors *m* as desired. Normally, conduit blocks of the type produced by machine A will contain nine conduits or ducts. However, blocks having a lesser number, some of which are also widely utilized, may be as easily produced. Consequently, on order to make a block with less than nine ducts, it is only requisite to de-energize such of the motors *m* as necessary. Manifestly, machine A could be built with any number of motors rather than merely nine and, accordingly, the present invention is not limited to a machine having only nine such motors.

The lower ends of dowel pin cores 108 and shafts 8 together with the packing heads *p* thereon extend through openings 33, 33' respectively formed in the base wall 34 of a hopper box 35; said openings 33' being of sufficient diameter to freely accommodate rods 101. Hopper box 35 is provided with upstanding side and end walls, as at 36, and is presented transversely between columns 1, 1'; there being sleeves or bearing housings 37, 37' for respective disposition about said columns 1, 1' engaged to the opposite sides of said hopper box 35 through connecting support portions 38, 38'. Each sleeve 37, 37' is engaged on its outer side, as through a bracket 39, 39', with the upper end of a piston 40, 40', respectively, of a vertically presented hydraulic cylinder 41, 41', respectively, the lower ends of which latter are mounted upon supports 42, 42', respectively, anchored at their lower ends upon base structure 2. Thus, pistons 40, 40' are axially parallel to columns 1, 1' and adapted upon their upward stroke to effect a lifting of hopper box 35 while, conversely, upon downward movement, to cause descent of the same, for purposes presently appearing.

Mounted upstandingly upon the upper surface of base wall 34 of box 35 are four vertical, spaced apart housings

43, for compression springs 44, which are encirclingly disposed about elongated rods 45; the upper ends of said springs 44 bearing against the upper end wall of the related housing 43 while the lower ends bear against the upper surface of a stripper plate 46 located below hopper box 35 in planar parallel relationship to base wall 34 thereof. Said rods 45 are fixed at their upper ends within housing 43 while the lower ends project freely through openings (not shown) formed in stripper plate 46 with a retaining nut 48 being mounted upon the projecting end of each to serve as a detent for preventing disengagement from stripper plate 46. Thus, said springs 44 bias stripper plate 46 into downwardly spaced relationship with respect to hopper box 35. Provided on opposite side portions of base plate 34 of hopper box 35 is a pair of guide pins 50 depending downwardly therefrom for slideable reception within sleeve-like members 51 formed on stripper plate 46, whereby said guide pins 50 will maintain hopper box 35 and stripper plate 46 in proper aligned relationship. Said stripper plate 46 is provided with openings 54, 54' which are respectively aligned with the openings 33, 33' of base wall 34 of hopper box 35, for passage therethrough of packing heads *p* and their associated shafts 8 and rods 101 and their cores 108, respectively. Secured to the under surface of stripper plate 46, as by bolts, is a flat, forming plate 111 having openings 114, 114' in registration with, and of like diameter as, openings 54, 54' respectively, of said stripper plate 46. However, the lower ends of openings 114 are encircled by a chamfered rim 115 providing an upwardly and outwardly directed bevel for purposes presently appearing. Suitably mounted upon the under surface of stripper plate 46 for projection downwardly therefrom is a plurality of spaced, elongated, mold guide members 55 for properly locating and maintaining a mold box B in operating position, as will be described more fully hereinbelow.

Referring now to FIGURE 3, there is shown a circular turntable 56 adapted for rotation about a vertical shaft 57 journaled within base structure 2, there being a plurality of rollers 58 provided on the periphery of said turntable 56 for assisting same during revolution as well as preventing any planarwise twisting or misalignment thereof. Carried on said turntable 56 is a pair of diametrically opposed pilot or guide plates 59, 59', each of which is provided with a plurality of apertures 60 for alignment with apertures 54, 114, and 33 of stripper plate 46, forming plate 111, and hopper box 35, respectively, for extension therethrough of packing heads *p* (see FIGURE 5), when said pilot plates are in operative position. Each pilot plate 59, 59' embodies a plurality of upstanding mold guides 61 for supporting and locating the lower end of mold box B, as the same is disposed upon a pilot plate. It will be noted that with turntable 56 in the position shown in FIGURE 3, pilot plate 59' will be presented substantially intermediate the lower ends of columns 1, 1', and thus, is in operative position, while the other pilot plate 59 is presented in, what might be termed, "preparatory position" in that it is accessible for mounting thereon of an empty mold box B, readied for being rotated into operative position upon completion of the molding operation within the mold box disposed upon pilot plate 59'. Although not depicted in the drawings, and hence not constituting a part of the present invention, there is provided with turntable 56 a system of micro-switches for assuring proper positioning of plates 59, 59', as machine 9 will be rendered inoperative by said switches unless the said plates are accurately positioned.

Mold boxes B as used with the present invention are of general four-sided construction, being preferably of cast aluminum, and elongated commensurately for the desired length of conduit block to be formed therefrom. Said mold boxes B are constituted of wall-forming sections 62, which are engageable at their meeting edges by readily manipulated latch members 63 so as to provide an enclosed four-sided receptacle for the mold material.

At the lower end of the wall-forming sections 62 of mold box B is a continuous, inwardly projecting base shoulder 64 adapted for supporting a base pallet 65 which is undercut along its periphery to define an overhang 65' aligned with the said shoulder 64, but with the height of such overhang 65' being slightly greater than the height of shoulder 64 so that when said pallet 65 is in position upon the particular pilot plate, there will be normally an intervening spacing therebetween as at s in FIGURE 5. Pallet 65 is provided with a series of openings 66 for alignment with the openings 60 in pilot plates 59, 59' for projection therethrough of packing heads p. About the upper ends of each of said openings 60, pallet 65 is formed, as by casting, to present a chamfered rim 116, being a downwardly and outwardly directed bevel. Also provided in pallet 65 are openings 117 having a diameter for permitting extension therethrough of dowel pin cores 108 (FIGURE 5), being thus aligned with openings 54' of forming plate 111 but of relatively reduced diameter. Each pilot plate 59, 59' contains openings 70 for alignment with openings 117 to accommodate cores 108.

In the operation of machine A, with the same in initial or starting position, as shown in full lines in FIGURE 1, and mold box B disposed upon pilot plate 59' between columns 1, 1' beneath stripper plate 46 and forming plate 111 which latter will be disposed upon the upper end thereof, and with mold guides 55 assuring proper location of the box B, the operator, by suitable means, actuates the hydraulic system comprising cylinders 16, 16', 41, 41', causing head 3 to descend and effect movement of hopper box 35 for lowering of same to present it into immediate overlying abutting relationship upon stripper plate 46, thus compressing springs 44 and causing guide pins 50 to extend downwardly. It will be seen that the firm disposition of hopper box 35 upon stripper plate 46 will stabilize the latter together with forming plate 111 to avoid any undesired turning, or shifting movement of mold box B during the molding operation, as might be produced under torque developed by shafts 8. With motor head 3 in full down position packing heads p and dowel pin cores 108 will project through the aligned openings 66, 60, and 117, 70 in the pallet 65 and pilot plate 59', respectively (FIGURE 5). The operator may then easily cause molding materials, such as mixed concrete, cement, or the like, to be delivered to mold box B through the openings 33 of said hopper box 35 and the aligned openings 54 and 114 of stripper plate 46 and forming plate 111, respectively, it being noted that there will be adequate space for the descent of such material, as such openings are of greater diameter than that of the shafts 8 projecting therethrough. The molding material may be delivered to the hopper box 35 in any suitable manner, such as, by conveyor, and the like, and the same may be easily fed to the mold box B, by hand, through the said openings, as above described. After the molding material has been presented to the mold box B so as to fill the voids or open spaces therein, between and about the shafts 8 and packing heads p, and about rods 101 and dowel pin cores 108, hydraulic motors m are energized so as to effect rotation of shafts 8 and substantially simultaneously therewith hydraulic cylinders 16, 16' are caused, as by appropriate manipulation of a conveniently located hand lever, to effect a retracting or lifting movement of their related pistons 17, 17' so as to cause ascent of motor head 3. Thus, shafts 8 with their related packing heads p will be rotating and traveling axially upwardly through the molding material within mold box B with each packing head p effecting formation within the block b to be produced, of a duct d having a diameter substantially the same as the outside diameter of said packing heads p, while rods 101 will be simultaneously carried upwardly causing a continuous passage or bore e having a diameter substantially that of cores 108 to be formed in block b. As rods 101 are raised during the molding and forming operation, the mold material will flow in-

wardly against the outer face of core 108, thereby filling the annular space temporarily developed by the differential in diameters of said rods 101 and their related cores 108. It is to be particularly noted that this action is reliably facilitated by the coaction between the tapered terminals 105 of rods 101 and the packing action of heads p, since as the latter rotate mold material will be forced radially outwardly into contact with said tapered terminals 105 for deflection downwardly therefrom for dis-
10 position about cores 108.

By virtue of the relatively loose or floating fit of rods 101 within their respective collars 100, and through their pin-engaged inter-engagement, the same may freely swing or swivel and thus relatively "give" upon encountering any non-resisting force, and also thereby permit an operator to guide said rods 101 into the appropriate openings should there, for any undetermined reason, be accidental non-registration. Accordingly, the clearance at the upper ends of said rods 101 will allow for limited upward movement of said rods upon striking any object at their lower ends, as through inadvertent misalignment of openings 33' in hopper box 35. Rods 101 are thus adapted to avoid damaging impact with any unexpected obstacles during the forming operation. This aforesaid loose fit prevents 20 rod or core breakage, which should occur with costly frequency if said rods 101 were rigidly mounted on machine A.

Passages e extend from end to end of the formed block b and are adapted for receiving dowel pins (not shown) 30 which are customarily utilized during installation for interconnecting abutting conduit blocks. By use of the present invention a formed block b may be cut into units of varying length having the dowel pin openings extending therethrough. Heretofore, in forming conduit blocks, 35 it had been the practice to provide dowel pin openings at only the upper and lower ends of the blocks, which openings were not connected, and relatively short in extent, so that upon cutting same into smaller sections, it was necessary to provide requisite dowel pin openings 40 therein by an independent operation.

The chamfered rims 115, 116 on forming plate 111 and pallet 65, respectively, cause the formed conduits d to be beveled or flared at their upper and lower ends, as at g, as may best be seen in FIGURE 11. The provision 45 of such beveled or chamfered portions allows for any accidental non-registration of adjacent conduit blocks b when in installed position so that the danger of cutting or rupturing of the insulation or covering of any cables received within the ducts d thereof is avoided. Prior 50 to the present invention ducts of conduit blocks were of constant diameter throughout their length and thereby presented a relatively sharp edge at each end which would cause cutting of cable insulation should adjacent blocks be out of alignment. Consequently, the provision of the 55 chamfered rims in machine A is productive of a feature in the resulting blocks which will permit of error in the block-laying operation so as to prevent costly damage to cables passing therethrough.

By the use of the floatingly mounted dowel pin cores 60 of the present invention, there are also overcome the various disadvantages heretofore generally accepted, resulting from the use of the short, dowel pin-forming members, embodied in currently used machines, provided for upward extension into the mold material, for development of the lower end openings. These short members have been subjected to breakage or bending through customary, all too frequent non-alignment with the related openings in the pallet, and have also caused cocking or tilting of the pallet with expected damage or imperfection 65 in the block being formed.

When the packing heads p and cores 108 have been withdrawn from the mold box B, that is, when motor head 3 is in full upward position as shown in full lines in FIGURE 1, the same will close the normally open limit switch, whereby hydraulic cylinders 41, 41' are 70

actuated for raising hopper box 35 into the position shown in full lines in FIGURE 1, thereby causing release of tension upon springs 44 so that stripper plate 46, together with attached forming plate 111, will be presented spacedly downwardly below hopper box 35. By such withdrawing action of hopper box 35 the downward pressure upon mold box B is removed and thereupon turntable 56 may be rotated so as to present an empty mold box into position preparatory to the next molding operation and to present the mold box B containing the fully molded conduit block b in position for removal from machine A. The latter may be transported from turntable 56 by any suitable means, such as, preferably, by a small hand cart, and by such removal it will be noted that pallet 65 is freed to descend, through gravity, into seated, abutting relationship upon shoulder 64 of mold box B and in so moving the same will effect a stripping of the molded block b from the side walls of mold box B, thus breaking the vacuum which will have developed therein. After removal from turntable 56, the mold box B is split as by disengagement of latch elements 63 to allow freeing of the formed conduit block b. It will thus be seen that the said block contains ducts d having beveled or flaring ends as at g, which correspond to the various packing heads p, and four smaller diameter passages e formed by dowel pin cores 108.

The said conduit block b thus contains nine ducts d, but it is easily seen that a block containing six ducts, or any number of ducts up to nine could be as easily formed merely by utilizing only the corresponding number of shafts 8 and packing heads p.

Although pallet 65 and forming plate 111 are shown as having the chamfered rims 116, 115, respectively, integrally formed thereon, such as, by casting, and the like, it is to be recognized that such rim portions may be independent elements for detachable engagement upon the related carrying member. An example of such is shown in FIGURE 8, which reveals a section of a plate 111' such as, a forming plate, having openings 120 extending therethrough; said openings 120 being tapped for receiving the threaded necks or bushings 122 of inserts 123, as formed of nylon, metal, or the like. Said inserts are of such length as to project at one end beyond the engaged plate and to be provided in such extended portion with an encircling chamfered rim 124; there being a shoulder 125 for abutment against the adjacent face of the plate 111'. Obviously, inserts 123 may be used for forming the upper or lower ends of the ducts d of the block b being molded, by application within the requisite plate, the openings are of relatively increased diameter to accommodate such inserts 123, it being recognized that the inside diameter of said inserts is of such extent as to permit extension therethrough of packing heads p.

Thus, machine A is easily operated and is consistent and reliable in operation so as to produce conduit blocks of uniform character and of great strength and durability. Furthermore, the machine is so contrived that the molding operation may be substantially continuous so that maximum production may be achieved.

The continuous, unbroken character of dowel pin openings e permit of ready inspection by subjection to light, so that any inadvertent malformations will be readily noted. This precautionary feature was not possible with the short openings provided in blocks heretofore.

It should be understood that changes and modifications in the formation, construction, arrangement, and combination of the several parts of the conduit block making machine may be made and substituted for these herein shown and described without departing from the nature and principle of my invention.

Having thus described my invention, what I claim and desire to secure by Letters Patent is:

1. A conduit block making machine adapted for receiving a mold box for moldable material comprising a frame, a head mounted on said frame and adapted for reciprocal vertical travel therealong, prime moving means carried on head, a plurality of elongated, vertically presented shafts adapted for rotation by said prime moving means and carried by said head for downward extension therefrom, a plurality of elongated rod members supported from said head for movement therewith being in downward extension therefrom in normally axial parallelism with said shafts, said rod members being of less diameter than said shafts, each rod member being positioned between at least two shafts, a packing head carried on the lower end of each shaft, each rod member being of slightly less length than the combined lengths of each shaft and its associated packing head and means located spacedly downwardly of said head for engaging the lower end of the mold box for supporting and positioning same for reception at its lower end of the lower portions of said shafts and rod members when said head is in lowered position whereby upon upward travel of said head said shafts and rod members will be drawn through the moldable material for formation of openings therein extending from end to end of the block formed.
2. A conduit block making machine as defined in claim 1 and further characterized by each rod member being adapted for limited rockability about its support from said head, each rod member being tapered at its lower end.
3. A conduit block making machine as defined in claim 1 and characterized by each rod member comprising a holder element and a core member secured in the lower end portion of the related holder element, each holder element having a tapered portion adjacent its connection to the related core member, and each core member being of relatively reduced diameter with respect to its associated holder element.
4. A conduit block making machine as defined in claim 1 and further characterized by a pallet provided at the lower end of said mold box and having openings for projection therethrough of the packing heads of said shafts and the lower ends of said rods, whereby upon upward travel of said heads, continuous, duct-like openings will be formed by said shafts and said rods in a resulting conduit block, which openings extend from end to end of such block.
5. A conduit block making machine as defined in claim 4 and further characterized by each rod member being located equidistant from four shafts.
